DISAPPEARING WALL BED

Harvey H. Hall, Denver, Colo.

Application June 1, 1936, Serial No. 82,735

2 Claims. (Cl. 5—133)

This invention relates to an electrically operated folding wall bed and has for its principal object the provision of a highly efficient and safe mechanism for opening and closing the bed, which will eliminate the complicated and expensive operating screws, cranks, levers, etc., usually employed for controlling such a bed.

Another object of the invention is to provide an efficient, light weight, easily installed device which will open and close a wall bed without manual exertion; which can be stopped, started, or reversed at any position in its travel; which, should the electrical supply be interrupted for any reason, can be quickly and easily adapted for manual operation; and which, cannot be operated while a person is upon the bed.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a side elevation of the improved bed in place in a wall niche. This view is taken on the line 2—2, Fig. 3. The bed, however, is shown in the elevated or closed position.

Fig. 2 is a similar view illustrating the bed in the open position.

Fig. 3 is a plan view of the head portion of the bed, taken on the line 3—3, Fig. 2.

Fig. 4 is an enlarged detail section taken on the line 4—4, Fig. 3.

Fig. 5 is a similarly enlarged view, taken on the line 5—5, Fig. 3.

Fig. 6 is a diagram of the wiring system of the improved bed.

Fig. 7 is a face view of the control switch.

The bed is arranged for position in a niche or compartment 10 formed in the wall of the room.

The compartment may be formed with a door casing 11 upon which suitable doors may be mounted for enclosing the bed when in the closed position.

The improved bed comprises a spring frame 12 of angle iron or any other suitable material for supporting the usual bed springs 13. At the foot of the bed, the usual ornamental foot board 14 is rigidly secured to the frame 12, and a pair of legs 15 are also hingedly suspended from the foot of the frame 12. At the head, the frame 12 is turned

upwardly to form a rigid head frame 16. The head frame is solidly braced from the spring frame 12 by means of suitable rigid braces 17. The head frame 16 is relatively low and does not project above the usual mattress when the latter is in place on the springs 13. A head board 18 is pivoted to the rigid frame 16, as indicated at 19. The frame 16 prevents the head 18 from swinging outward but allows it to swing inward.

The head of the bed is supported by means of 10 a hinged diagonal brace 20 at each side. The braces 20 extend from pivots 21 at their upper extremities to pivots 22 at their lower extremities. The pivots 22 are mounted in guide castings 23 which extend upwardly at each side of the head 15 and are secured to the side walls of the compartment 10. The guide castings 23 are formed with vertical roller tracks 24 and the head of the frame 12 is provided with roller studs 25 which travel in the tracks 24 as the bed is raised and lowered. The raising and lowering is accomplished by means of an electric motor 26 which rotates a cross shaft 27 through a medium of a worm drive transmission 28. The cross shaft is mounted in two bearing blocks 29, there being one block adjacent each extremity of the shaft 27, upon which a pair of flexible cables 31 are alternately wound and unwound.

Each cable is secured at its one extremity to its spool 30 and at its other extremity to a cable bar 32. The cable bars 32 are removably attached to the rigid head frames 16 by means of wing nuts 33 and extend upwardly from the rigid head 16 to a connection with a cable 31.

A spring tube 34 is secured in and extends upwardly from each of the bearing blocks 29. The upper extremity of each of the spring tubes is longitudinally slotted, as indicated at 35, to expose a compression spring 36 contained within the tube. A pair of spring levers 37 is secured to the rigid head 16, there being one of the levers 37 in alignment with each of the spring tubes 34 so that the upper extremity of the lever will enter the slot 35 and compress the spring 36 when the bed is closed.

The motor 26 is automatically stopped at each extremity of movement of the bed by means of a "three-way" switch 41 of the toggle type. The operating lever of the switch 41 is connected through a flexible member 42 with the rigid head 50 frame 16 so that as the bed reaches its lowermost position the toggle is snapped upwardly and as the bed reaches its raised position the toggle is snapped downwardly. The motor is manually started by means of control switch 39 which may

be located in a convenient position on the compartment casing 11. The face of the control switch is shown in Fig. 7.

A suggested circuit diagram of the electrical connections to the driving motor is illustrated in Fig. 6. In this diagram the main feed wires are indicated at 38. One of the feed wires leads directly to armature of the motor 26. The second feed wire is in series with an electric over-load circuit breaker 40. The control switch 39 is of the three-pole, double-throw type. One of the poles, indicated at 43, cooperates with the switch 41 to form a three-way control circuit 44 so that after the switch 41 has broken the circuit to the motor it can be again closed by swinging the pole 43 in the opposite direction. The second feed leads through the overload circuit breaker 40 and the three-way circuit 44 to the motor.

20 The remaining two poles of the switch 39 are employed to reverse the current flow relation between the motor armature and field so as to reverse the direction of rotation of the motor.

Let us assume that the bed is in the open position of Fig. 2 and that it is desired to fold it into the compartment 10. The operator throws the reversing switch 39 to the "up" position. This completes the circuit through the three-way switch 41 and the pole 43 to the motor 26 and also connects the armature-field circuit of the motor to cause the latter to rotate in the proper direction to elevate the bed.

The motor drives the shaft 27 so as to cause the cables 31 to be reeled upon the spools 30. 35 The cables pull downwardly upon the head of the frame 12, causing the roller studs 25 to travel downwardly in their tracks 24. The braces 20 act as fulcrums so that as the head moves downwardly, the foot will move upwardly. This action continues until the frame 12 passes into the compartment past the dead center position of the brace pivots 21 and 22. As the bed approaches this dead center position, the levers 37 enter the slots 35 and compress the springs 36 which act as a cushion to stop the motion of the bed. This also causes the flexible member 42 to 45 actuate the three-way switch 41 to the open side of the circuit 44 thereby stopping the motor 26. When the motor stops the springs 36 remain 50 under compression.

When it is desired to lower the bed, the control switch 39 is thrown to the "down" position, which causes the current to flow through the closed side of the three way circuit 44 to the 55 motor so that the shaft 27 will be rotated in the reverse direction. This unreels the cable 31. Since the cables 31 can not exert a pushing action to force the bed over the dead center position to the point where gravity will operate thereon, the springs 36 are provided. These springs will expand as soon as the cables 31 begin to relax so as to push upon the levers 27 upwardly to swing the frame 12 outwardly past the dead center position. The weight of the bed will then 60 keep the cables taut as they unreel.

The legs 15 are actuated solely by gravity to swing to the suspended or supporting positions.

The head of the bed 18 cannot move backwardly since it is prevented by the rigid portion 16. A loose flexible spring 43 constantly pulls the head backwardly so that when the bed folds it will be drawn to the position of Fig. 1 against the back 5 wall of the compartment 10.

It is desired to call attention to the overload circuit breaker 40. This may be any of the standard types for opening an electric circuit when the load thereon reaches a certain pre-determined quantity. This circuit breaker is set so that it will open the circuit should the weight to be lifted by the motor exceed the normal weight of the bed and bedding and acts as a safety to prevent the bed from being accidentally 15 or intentionally closed while occupied.

It is also desired to call attention to the removable cable bars 32. It might happen that the electrical supply would fail when it became desirable to lower the bed. In such a case, the wing 20 nuts 33 could be removed to release the bars 32 and their cables so that the bed could be raised or lowered by hand.

While a specific form of the improvement has been described and illustrated herein, it is desired 25 to be understood that the same may be varied, within the scope of the appended claims, without departing from the spirit of the invention.

Having thus described the invention, what is 30 claimed and desired secured by Letters Patent is:

1. An electrically operated folding bed comprising: a bed frame; means for hingedly supporting said frame so that it can swing upwardly from open to folded position; electrically operated 35 means for elevating said frame to the latter position; levers projecting from said frame; spring tubes positioned in the paths of said levers and provided with slots for the reception of said levers and springs contained within said tubes to 40 be compressed by said levers as said bed frame reaches its fully elevated position.

2. An electrically operated folding bed comprising a bed frame, a fulcrum tiltably mounting the frame at a point in advance of the head 45 end thereof for vertical swinging movement from a lowered horizontal position to a raised vertical position, vertical guides slidably engaged by the head end of the bed frame back of its points of pivotal mounting for guiding the bed frame during its swinging movement, a rotatably mounted shaft extending transversely of the bed adjacent lower ends of the guides at the head end of the bed frame, bars disposed vertically against the rear face of the head of the bed frame and detachably secured adjacent opposite sides of the bed frame at a point above the fulcrum when the bed frame is in its lowered position, reels carried by said shaft, flexible members wound upon said reels and extending upwardly and 60 secured to said bars, and an electric motor for rotating said shaft to wind the flexible members upon the reels and exerting pull upon the head end of the bed frame to swing the bed to the raised position.
